CLAIM

The ornamental design for a fishing pole holder, as shown and described.

DESCRIPTION

FIG. 1 is a top isometric view of fishing pole holder showing my new design;

FIG. 2 is a bottom isometric view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a top isometric view, laterally connected to a C-clamp at the bottom of the fishing pole holder;

FIG. 10 is a bottom isometric perspective view, laterally connected to a C-clamp at the bottom of the fishing pole holder; and,

FIG. 11 is a top isometric view of an alternate embodiment of the present invention comprising a pointed end.
